UNITED STATES PATENT OFFICE.

CLARENCE L. BAIR, OF SAN FRANCISCO, CALIFORNIA, ASSIGNOR TO AUTO SPECIALTIES MANUFACTURING COMPANY, A CORPORATION OF CALIFORNIA.

VEHICLE-TOP BOW-HOLDER.

1,010,110.

Specification of Letters Patent. Patented Nov. 28, 1911.

Application filed May 26, 1910. Serial No. 563,480.

To all whom it may concern:

Be it known that I, CLARENCE L. BAIR, a citizen of the United States, residing at the city and county of San Francisco and State of California, have invented certain new and useful Improvements in Vehicle-Top Bow-Holders, of which the following is a specification.

My invention relates to that class of bow-holders for vehicle-tops in which the bows when folded back are separated and independently supported in sockets formed between two relatively movable members, said class being typified by that holder shown 15 in Letters Patent of the United States No. 866,416, granted to me Sept. 17, 1907.

My present invention consists in certain improvements which are especially applicable to a holder of this type; which improvements have for their general objects increased efficiency in the use of the device, and maximum strength with minimum weight consistent with the cost of materials employed in its construction. How these 25 objects are attained, together with the details of the several improvements will hereinafter fully appear.

Referring to the accompanying drawings—Figure 1 is a perspective view of the holder showing it open, ready to receive the bows of the vehicle-top. Fig. 2 is a side elevation of the holder showing it closed on the bows, the latter being in cross section, and the movable arm being shown in partial 35 vertical section in order to show the engagement of the knobs in the bows with the socket seats in the arm. The knobs in this figure are non-adjustable. Fig. 3 is a broken sectional view of the holder showing a form 40 of knob engagement in which the knob is an adjustable one, being screwed into a suitable socket in the bow. Fig. 4 is a similar broken section to show a form of knob-engagement in which the knob is adjustable 45 being screwed through and carried by the arm and adapted to seat in a socket in the bow. Fig. 5 is a similar broken section to show the adjustable knob of Fig. 4, but which in this case engages the bow through 50 the intervention of a socketed protecting band carried by said bow. Fig. 6 is a broken sectional view showing a form of engagement in which projections on the movable arm are adapted to enter a protecting 55 pocket seated in the bow. Fig. 7 is a view of the holder as adapted for the lighter tops of buggies, said holder having a relatively extensive rest or support for the bottom bow, and a securing lug below said support.

Referring to Fig. 1, the numeral 1 indicates the stock of the holder. This stock, for the sake of lightness and strength, is best made of a three-quarter tubular section. At its top, on its inner face, it is inclined or sloped back as shown at 2, in order to facilitate the entrance of the bows and permit them to pass without damage. The top of the stock is grooved out at 3 to form a seat for the point of the movable 60 arm, and also to form ears 4, in which the ends of the connecting link are pivotally seated. The stock at its lower end is fashioned to a knuckle 5 to receive on each side the ears of the knuckle of the movable arm; 65 and, finally, said stock, about the middle is formed with the securing lug 6, which has a vertical hole 7 through it and also a horizontal hole 8, in order to fit it to either a vertical or a horizontal fastening iron ex- 70 tending from the vehicle body. A set screw 9 in the end of the lug is used to fasten it on said iron. 10 is the movable arm. It is hinged at its lower end by a forked knuckle 11 to the knuckle 5 of the stock 1, 75 the sides of the knuckle 11 lying outside the knuckle 5 and so recessed thereon as to be substantially flush with the stock thus forming a neat hinge joint, and providing if required for a limited movement of the hinge 80 by properly shaping the engaging surfaces. The arm 10 is formed with a series of fingers or bow-lifts 12, projecting toward the stock and making a series of bow receiving and separator sockets 13. The inner ends 85 of the bow-lifts are well rounded as shown, to avoid any possible injury to the bows, when passing between them. The upper end of the arm has a shouldered point 14, and a thumb piece 15, serving the double 90 purpose of a locking contact lug and a convenient means for swinging the arm open. The arm is also formed, for the sake of strength, with a back rib 16. 17 is the locking lever, formed with a locking lug 18 at 95 right angles. This lever is pivoted at its angle to the connecting link 19 which is best formed of a springy nature. The other end of the link 19 is pivotally connected in the ears 4 at the top of the stock 1.

Referring now to Fig. 2, it will be seen that the arm 10 has been closed, so that its separator sockets 13, in conjunction with the opposing stock, encircle the bows 20. In this closed position the top point 14 of the arm 10 is seated in and shouldered against the top groove 3 of the stock, and said arm is locked in this closed position by the contact, under pressure, of the locking lug 18 of lever 17 with the back of the thumb piece 15. The unlocking of the arm 10 is effected by lifting and upward swinging of the lever 17 to relieve the contact of said parts. Heretofore it has been deemed sufficient to simply embrace the bows by the separator sockets and hold them with more or less pressure in said sockets and against the stock; and to protect the bows from friction by a band such as I show in my former patent, or to line the sockets with some cushion material. My present invention, however, contemplates and embraces a more direct and positive connection between the movable arm and the bows, which connection will have the effect of positively steadying them, and prevent their tendency to vibrate, and will, in effect, hold them practically out of direct contact with the fingers or lifts of the arm. This connection may assume various forms, several of which I herein show. The form shown in Fig. 2 consists of a knob-headed pin 21 driven into the bows. The knob-head 22 of this pin projects from the surface of the bow and finds a seat in a complementary socket 23 formed in the arm 10. In order to determine the precise place at which the pin is to be driven into the bow, a small hole 24 is left in the arm 10 leading to the socket 23; through which an awl may be passed to mark the place on the bow for the pin. In Fig. 3, I illustrate this connection as an adjustable one, formed by a screw-pin 24', having a knob-head 25. This screw-pin is seated in the bow and is adjustable therein in a suitable socket, so that the position of its knob head 25 may be nicely regulated relatively to its seat in the socket 23 of the arm 10.

In Fig. 4, I show another arrangement of adjustable knob-engagement. In this form the knob head 26 has a screw-shank 27 which is screwed into the arm 10, and said knob engages a socket 28 in the bow.

In Fig. 5, I show the knob-head 26 of the screw 27 of Fig. 4, engaging a socket 29 in a protecting band 30 which is carried by the bow.

In Fig. 6, I show a protecting pocket 31 pinned in the bow, adapted to receive projections 32 formed on the arm 10.

For the tops of lighter vehicles such as buggies, I form the base of the stock 1 with a relatively long extension rest 33 which will serve as a support for the bottom bow; and under this rest is formed the securing

lug 34, the aperture in which may be made circular or square to receive the prop-iron, according to its shape, of said vehicle.

Having thus described my invention, what I claim as new and desire to secure by Letters Patent is—

1. A vehicle top bow holder comprising a stock having its upper end grooved to form side ears, an arm hinged to the lower end of said stock and formed with a series of lifts coacting with the stock to provide separator sockets for the bows, said arm having at its upper end a shoulder adapted to abut the side ears of the stock when the arm is closed and a projection extending from said shoulder and arranged to project between said ears of the stock, a contact piece on said arm in rear of said shoulder, a locking lever having a contact lug to lock behind the contact piece of the arm, and a spring link having its ends pivotally connected to the upper portion of said arm and to said locking lever. 75

2. A vehicle-top bow-holder comprising a stock; an arm formed with a series of bow-lifts coacting with the stock to provide separator sockets for the bows; a hinge connection at one end between the stock and arm; means for releasably locking them together at the other end; and interengaging instrumentalities to positively connect the arm and bows, releasable by the separation of the arm from the bows. 90

3. A vehicle-top bow-holder comprising a stock; an arm formed with a series of bow-lifts coacting with the stock to provide separator sockets for the bows; a hinge connection at one end between the stock and arm; means for releasably locking them together at the other end; and relatively adjustable interengaging instrumentalities to positively connect the arm and each of said bows, releasable by the separation of the arm from the bows. 100

4. A vehicle-top bow-holder comprising a stock; an arm formed with a series of bow-lifts coacting with the stock to provide separator sockets for the bows; a hinge connection at one end between the stock and arm; means for releasably locking them together at the other end; and interengaging instrumentalities to positively connect the arm and each of said bows, releasable by the separation of the arm from the bows, said instrumentalities consisting of projections 115 on one part seating in a socket in the other. 120

5. A vehicle-top bow-holder comprising a stock; an arm formed with a series of bow-lifts coacting with the stock to provide separator sockets for the bows; a hinge connection at one end between the stock and arm; means for releasably locking them together at the other end; and adjustable interengaging instrumentalities to positively connect the arm and each of said bows, releasable 125 130

able by the separation of the arm from the bows, said instrumentalities consisting of projections on one part seating in a socket in the other.

5. 6. A vehicle-top bow-holder comprising a stock; an arm formed with a series of bow-lifts coacting with the stock to provide separator sockets for the bows; a hinge connection at one end between the stock and arm; 10 means for releasably locking them together at the other end; and interengaging instrumentalities to positively connect the arm and each of said bows, releasable by the separation of the arm from the bows, said instrumentalities consisting of knobs on one part seating in complemental sockets in the other part.
7. A vehicle-top bow-holder comprising a stock; an arm formed with a series of bow-lifts coacting with the stock to provide separator sockets for the bows; a hinge connection at one end between the stock and arm; means for releasably locking them together at the other end; and interengaging instrumentalities to positively connect the arm and each of said bows, releasable by the

separation of the arm from the bows, said instrumentalities consisting of knobs on one part seating in complemental sockets in the other part, said knobs being adjustably 30 mounted.

8. A vehicle-top bow-holder comprising a stock; an arm formed with a series of bow-lifts coacting with the stock to provide separator sockets for the bows; a hinge connection at one end between the stock and arm; 35 means for releasably locking them together at the other end; and interengaging instrumentalities to positively connect the arm and each of said bows, releasable by the separation of the arm from the bows, said instrumentalities consisting of knobs on the arm, and protecting bands on the bows provided with complemental sockets to receive 40 said knobs.

In testimony whereof I have signed my name to this specification in the presence of two subscribing witnesses.
